(57) **CLAIM**

I claim the ornamental design for an umbilical cord clamp, as shown and described.

DESCRIPTION

FIG. 1 is a left and bottom perspective view of the umbilical cord clamp of the new design.

FIG. 2 is a perspective view thereof shown in closed position.

FIG. 3 is a side view of FIG. 1.

FIG. 4 is another side view thereof.

FIG. 5 is a top view of FIG. 1.

FIG. 6 is a bottom view thereof.

FIG. 7 is a front view thereof; and,

FIG. 8 is a back view thereof.

The broken lines shown in the figures represent portions of the umbilical cord clamp that form no part of the claimed design.
